UNITED STATES PATENT OFFICE.

JOSEPH A. HOEGGER, OF JERSEY CITY, NEW JERSEY.

DESIGN FOR A SHAVING MIRROR.

Application filed February 16, 1929. Serial No. 30,101. Term of patent 14 years.

To all whom it may concern:

Be it known that I, JOSEPH A. HOEGGER, a citizen of the United States, and a resident of Jersey City, Hudson County, New Jersey, have invented a new, original, and ornamental Design for Shaving Mirrors, of which the following is a specification, reference being had to the accompanying drawings, forming a part thereof.

I claim:

The ornamental design for a shaving mirror as shown.

JOSEPH A. HOEGGER.
